UNITED STATES PATENT OFFICE

91,603

DESIGN FOR A BUTTON

Leonard R. Carley, Watertown, Conn., assignor to
The Patent Button Company, Waterbury, Conn., a corporation of Connecticut

Application March 14, 1933, Serial No. 47,446

Term of patent 14 years

To all whom it may concern:

Be it known that I, LEONARD R. CARLEY, a citizen of the United States, residing at Watertown, in the county of Litchfield and State of Connecticut, have invented a new, original, and ornamental Design for Buttons, of which the following is a specification, reference being had to the accompanying drawing, forming part thereof, in which:

Fig. 1 is a top plan view, on an enlarged scale, of a button showing my new design;

Fig. 2 is a side elevation thereof;

Fig. 3 is a bottom plan view thereof; and

Fig. 4 is a diagrammatic sectional view of the button shown in Fig. 1 to illustrate the contour of the central element.

I claim:

The ornamental design for a button, as shown.

LEONARD R. CARLEY.
